UNITED STATES PATENT OFFICE

GEORGE A. AWALT, OF MINNEAPOLIS, MINNESOTA

STORM SASH HOLDER

Application filed January 27, 1930. Serial No. 423,692.

This invention relates to storm sash holders or retainers and has for one of its main objects to provide a simple but highly efficient storm sash holder, which may be manufactured at low cost and which will secure the storm sash in various open positions and lock the sash in closed position.

It is another object of my invention to provide a storm sash holder or latch, where-
10 in the sash may be secured in any desired open position within certain limits by means of a simple eccentric mechanism which co-
operates with one or more of the links or
other members connecting the storm sash
15 and the window frame.

Still a further object is to provide a holder for storm sash comprising a pair of links pivoted to an attachment bracket which may be secured to the storm sash or the
20 window frame, the said links diverging from the bracket and having at their outer ends
slidable connections with suitable guides se-
cured to the window frame or storm sash
25 as the case may be, said links working in
cooperation with simple locking or retaining
mechanism which is adapted to engage the
pivoted ends of the links to hold the storm
30 sash in any desired open position within
certain limits.

These and other objects and advantages
35 of the invention will be apparent from the
following description made in connection
with the accompanying drawings, wherein
like reference characters refer to similar
35 parts throughout the several views, and
wherein;

Fig. 1 is a horizontal cross section taken
40 through a window frame having the usual
lower sash and swinging storm sash mounted
thereon and having an embodiment of my
invention applied to the window sill and
45 storm sash, the storm sash being shown in
closed position and an open position of the
storm sash and my retaining device being
shown in dotted lines;

Fig. 2 is a vertical section taken on the
50 line 2-2 of Fig. 1, showing the storm sash
locked in closed position and illustrating the
structure and function of my eccentric re-
taining mechanism;

Fig. 3 is a fragmentary vertical section
55 taken on the line 3-3 of Fig. 2, showing
the preferred manner in which my retaining
mechanism may be mounted on an at-
tachment bracket;

Fig. 4 is a perspective view of one of the
links of my sash holder detached;

Fig. 5 is a front elevation of an elongated
attachment bracket provided with longitudi-
60 nal grooves, wherein the outer diverging
ends of the links are slidably mounted, the
grooved bracket as shown, being attached
to the sill of the window frame; and

Fig. 6 is a perspective view of a suitable
attachment bracket for carrying the pivot
65 for the inner ends of the links and the re-
taining or anchoring mechanism.

As shown in the drawings, my sash holder
is applied to a conventional storm sash X
70 of the swinging type usually hung from its
upper horizontal edge and connected by
straps or hinges to the head rail of the win-
dow frame. The window frame has the usual
sill S, blind stop B and lower sash Y,
75 the blind stop being spaced a sufficient dis-
tance from the outer edge of the window
casing or frame to accommodate the storm
sash X.

The embodiment of my invention illus-
trated includes a suitable attachment bracket
7, which, as shown, comprises a short angle
strip adapted to be readily attached to or
detached from the inner face of the storm
80 sash adjacent the lower edge thereof. Ad-
jacent its lower edge, the storm sash X is
preferably provided with a pair of screws
or bolts 8 having their heads spaced a short
distance from the face of the storm sash and
the vertical arm of bracket 7 is provided
85 with a pair of spaced locking apertures 7a
having enlarged lower portions for recep-
tion of the heads of screws 8 and relatively
narrow upwardly extending confining slots
7b communicating with said apertures. A
90 small aperture 7c may be formed in the hor-
izontal arm of the bracket 7 and the lower,
and reduced end of an upwardly projecting
pivot post 9 is extended through aperture
95 7c and riveted or otherwise secured to the
horizontal arm of bracket 7.

As shown, bracket 7 is adjustably connected with the sill of the window frame by means of a pair of links 10, said links having terminal eyes 10a which surround 5 pivot post 9, one disposed above the other for a purpose later to be described. The two links 10 diverge from pivot 9 toward the sill S. If desired, links 10 may be constructed from metal rods, and the eyes 10a flattened to increase the frictional area 10 between the portions of the links lapped on pivot 9.

The diverging ends of links 10 are provided with offset extremities 10b which underlie and slide in a pair of elongated slotted portions 11a formed in an elongated attachment bracket 11, preferably constructed in the form of a strip. Attachment strip 11, as shown, is secured to the window sill, 15 spaced some distance from the outer edge thereof and is provided with offset attachment flanges 11b at the ends thereof adapted to engage the sill and a central depressed attachment flange 11c also adapted to engage 20 the sill, suitable means, such as screws 12 securing said several attachment flanges to the upper surface of the sill. The slotted portions 11a of strip 11, as clearly shown 25 in Fig. 5, are spaced a short distance above the sill in order that the offset ends of links 10b may be nicely accommodated therebelow. An upstanding locking flange 11d is provided at the central attachment portion 30 of the strip for a purpose later to be described.

To securely hold the storm sash in a desired open position I provide simple but efficient mechanism mounted on the attachment bracket 7 and preferably carried by 40 upright post 9. As illustrated, a coiled spring or other elastic or compressible member 15 surrounds the lower portion of pivot post 9 beneath the eyes 10a of the links. The upper portion of pivot post 9 is preferably 45 slotted longitudinally from the upper end to a point some distance below the upper surface of the upper eye 10a. An eccentric 13 is accommodated in the slot of post 9 and is pivoted to the forked upper portion 50 of the post on a pin 14, which preferably extends at right angles to the axis of post 9. The working edge of eccentric 13 is adapted to engage the upper surface of the uppermost eye of the links 10 and I prefer 55 to shape the working edge of the eccentric in such manner that it will be moved to a dead center position by less than a 90° turn thereof. The spring 15 is of such length and expansibility that it will yieldingly hold the 60 two eyes 10a of the links against the edge of the eccentric with a considerable degree of friction.

Eccentric 13 is provided with a handle 13a extended in the direction of the sash 65 Y and terminating in a downturned hook

13b which when the storm sash is closed is adapted to engage and interlock with the upstanding locking flange 11d at the central attachment portion of the strip or bracket 70

Operation

The operation of my storm sash holder may be briefly described as follows:—

With the eccentric handle 13a in raised position, the storm sash may be swung outwardly to a desired open position within the limits provided, according to the length of links 10. Coil spring 15 causes the overlapping eyes of the links 10 to be yieldingly and frictionally held against the edge of the eccentric. In many instances, this frictional engagement of the eyes of the links is sufficient to hold the storm sash in open position. However, to positively retain the same, eccentric arm 13a may be swung downwardly causing the working edge of the eccentric to tightly clamp the lapped eyes 10a of the links against the top of the compressed spring 15. The slight yielding action of the spring 15 in cooperation with the eccentric affords a slightly better friction clamping device than if the spring were eliminated, although, of course, I contemplate the use of the eccentric device 90 with the overlapping eyes of the links without the interposition of the yieldable element or spring, all within the scope of my invention.

During the outward swinging movement 100 of storm sash X, the diverging ends of the links will, of course, slide inwardly guided by the slotted portions 11a of the sill bracket and will be limited in inward movement by the inner ends of the slots. The inner ends of said slots are spaced a sufficient distance apart so that links 10 when the storm sash is in full open position, will always diverge sufficiently to permit easy 105 sliding of their offset ends 10b when the storm sash is swung inwardly.

The handle 13a and hook 13b of the eccentric may be grasped and utilized as an operator for closing or opening the storm sash and when the storm sash is positioned 110 against the blind stop B the handle 13a may then be swung downwardly, the eccentric frictionally clamping the lapped ends of the links and the hook 13b having positive locking engagement at that time with the upstanding locking flange 11d of the sill attachment strip.

It will be seen that the attachment bracket 7 may be quickly removed from the storm sash by sliding the same upwardly to position the heads of screws 8 in the enlarged portions 7a of the attachment arm of the bracket. When the bracket 7 carrying the eccentric and pivot 9 is removed from the storm sash, the links may be swung or posi- 125 130

tioned to permit detachment of their offset ends 10b from the guides or slotted portions of the attachment strip 11.

While I have shown the bracket 7 and 5 pivoted ends of the links attached to the storm sash it is, of course, quite obvious that my device may be reversed, the bracket 7 being attached to the sill at the proper point thereof and the attachment strip 11 secured 10 to the storm sash, all within the scope of my invention.

From the foregoing description, it will be seen that I have provided a simple, highly efficient and comparatively inexpensive 15 storm sash holder, which may be secured by the cooperation of the links, eccentric and other working parts of my device to positively hold the storm sash in any desired open position within the limits provided. 20 The device, in addition, provides convenient operating mechanism by which the storm sash may be swung inwardly or outwardly and also effects the positive locking of the storm sash in closed position by the engagement of the hook 13b with the locking flange 11d.

It will, of course, be understood that various changes may be made in the form, details, arrangement and proportions of the 30 parts without departing from the scope of applicant's invention.

What is claimed is:—

1. In combination with a window frame and a storm sash swingably mounted therein, 35 a pair of attachment members, one adapted to be secured to said storm sash and one adapted to be secured to said window frame, a link pivoted at one end to one of said attachment members, connections between 40 the opposite end of said link and the other attachment member and an eccentric carried by said first attachment member having its working edge disposed in position to clamp against said link adjacent said pivot to secure said link against swinging movement.

2. In combination with a window frame and storm sash swingably mounted therein, a pair of attachment members, one adapted to be secured to said storm sash and one 50 adapted to be secured to said window frame, a pair of links pivoted to one of said attachment members and diverging therefrom, connections between the diverging ends of said links and said second attachment member, an eccentric carried by said first mentioned attachment member and having a working edge adapted to exert clamping pressure against said links adjacent their pivotal connection to retain said links 55 against swinging movement.

3. In combination with a window frame and storm sash swingably mounted therein, a pair of attachment members, one adapted to be mounted adjacent an edge of said storm 65 sash, and one adapted to be secured to said

window frame, a pair of links having ends pivoted to one of said attachment members, said links diverging therefrom, said second attachment member having guides therein extending substantially parallel with the 70 said edge of said storm sash, the diverging ends of said links being slidably mounted in said guides, and means adjacent the pivoted ends of said links for exerting clamping pressure against said links to secure the same against swinging movement. 75

4. In combination with a window frame and storm sash swingably mounted therein, a pair of attachment members, one adapted to be mounted adjacent an edge of said 80 storm sash and one adapted to be secured to said window frame, a pair of links having lapped ends pivoted to one of said attachment members on a common pivot, said links diverging from said pivot, said other attachment member having guides therein extending substantially parallel with the said edge of said storm sash, the diverging ends of said links being slidably mounted in said guides, and an eccentric mounted on said first 85 mentioned attachment member with its working edge disposed in position to clamp against a face of one of said links adjacent said common pivot to secure said links against swinging movement. 90

5. In combination with a window frame and storm sash swingably mounted therein, a pair of attachment members, one adapted to be secured to said storm sash and one 100 adapted to be secured to said window frame, one of said attachment members carrying a pivot post, a pair of links swingably mounted on said pivot post in lapped relation, connections between said links and said other attachment member, an eccentric supported 105 from said pivot post, and swingable on an axis extending at right angles to said post, the working edge of said eccentric being disposed in position to clamp against the face of one of said links to secure said links 110 against swinging movement.

6. In combination with a window frame and a storm sash swingably mounted therein, a pair of attachment brackets one adapted to be secured to said storm sash and one adapted to be secured to said window frame, one of said attachment members carrying a pivot post, a pair of links having ends pivotally connected with said post in lapped relation, said links diverging from said post, the upper end of said pivot post being forked, and an eccentric disposed within said fork and pivoted to said post on an axis extending at right angles to said post, the working edge of said eccentric disposed in position to clamp against the face of one of said links to force the pivoted ends of said links together and secure the same against swinging movement. 120

7. In combination with a window frame 130

and storm sash swingably mounted therein, a pair of attachment members, one adapted to be secured to said storm sash and one adapted to be secured to said window frame,
5. a pair of links pivoted to one of said attachment members and diverging therefrom, connections between the diverging ends of said links and said second attachment member, an eccentric carried by said first mentioned attachment member and having a working edge adapted to exert clamping pressure against said links adjacent their pivotal connection to retain said links against swinging movement and said eccentric having a projecting handle provided with a locking hook adapted to engage means on said second attachment member for locking the storm sash in closed position.

In testimony whereof I affix my signature.
